UNITED STATES PATENT OFFICE.

CHARLES RYAN, OF MOSMAN'S BAY, SYDNEY, AUSTRALIA.

FASTENER.

1,278,756.

Specification of Letters Patent. Patented Sept. 10, 1918.

Application filed March 4, 1918. Serial No. 220,322.

To all whom it may concern:

Be it known that I, CHARLES RYAN, a subject of the King of Great Britain, and residing at Mosman's Bay, Sydney, Australia, have invented new and useful Improvements in Fasteners, of which the following is a specification.

The present invention relates to improvements in apparel fasteners and has for its 10 principal object to provide a simple and durable connecting means which may be employed in lieu of lacings for connecting members or parts of an article of apparel. By the invention, it is possible to effect the 15 closure of an opening more readily and quickly than if a lace is employed and to provide a fastening which, while conforming to the surface over which it extends, will not become worn by use and will present 20 an attractive and ornamental appearance.

While the fastener hereinafter described is adapted for use with boots, shoes, leggings, gloves and corsets, it is particularly 25 adapted as a shoe fastening and is so illustrated in the accompanying drawing.

In the drawing Figure 1 is a perspective view of a portion of a boot or shoe having the improved fastener applied thereto;

Fig. 2 illustrates the manner of initially applying the fastener to the shoe;

Fig. 3 shows the fastener in position for engaging eyelets at the opposite side of the opening in the shoe upper when brought 35 into correct position;

Fig. 4 is a sectional view showing the fastener engaged with both sections of the shoe upper;

Fig. 5 is a detail view showing a slightly 40 modified form of the fastener;

Fig. 6 is a sectional view of the fastener, substantially on the line 6-6, of Fig. 4.

Referring to the drawings, it will be seen that the fastener essentially comprises two 45 bar-like members 1, preferably made of metal, of narrow rectangular or half-round form in cross section. Said members are provided at one end with suitable means for engaging eyelets 2, and have their opposite

50 ends connected by an integral transversely extending member 3. As shown the eyelet engaging means at the free ends of the members 1 are produced by bending said ends rearwardly to form slight hooks 4. The 55 members 1 are preferably slightly curved in

the direction of their length and near their connected ends are bent or curved slightly so that the transverse member 3 is carried inwardly slightly beyond the ends of said bars whereby, as shown for example in Fig. 60 4, it will lie beneath the body in which the eyelets 5 are mounted, through which eyelets the members 1 extend. Also, as shown in the drawings, said transverse connecting member 3 is bowed or curved slightly on its 65 lower or inner surface so that the fastener as a whole is permitted to have a slight rocking movement when in operative position which will permit it to adapt itself to the flexing or bending motion of the instep, 70 for example, and thus avoid any undesirable pressure or binding action thereon.

From the drawings, it will be seen that when the fastener has been passed through the eyelets 5, at one side of the opening in 75 a shoe upper, for example, the body of the upper will be grasped between the transverse connecting member 3 and the bars 1 so that there is little chance of the fastener being displaced or detached from the shoe 80 when not in use. The hooks 4 may be readily engaged in the eyelets 2 and as the transverse connecting member 3 is concealed, the fastener has the appearance of an ordinary 85 lacing.

As shown, the eyelets at the two sides of the opening to be closed are spaced uniformly and are all at the same distance from the edge of said opening. Therefore, the bar-like members 1 are substantially parallel, 90 throughout their length. In some instances, however, the eyelets 2 may be irregularly spaced or successive eyelets situated at slightly different distances from the edge of the opening and in this case the members, 6 95 6', of the fastener will be of different lengths, as shown in Fig. 5. Of course, the bar-like members need not be parallel but may diverge slightly according to the positions of the eyelets which are to be connected thereby. 100

The fastener may be of metal, enameled in black, tan or any other suitable color, and if desired, may be ornamented in any appropriate manner.

The manner of applying and using the 105 improved fastener will be readily understood and appreciated from the foregoing description and the drawing. It will be seen that the device provides for connecting two parts of an article as securely as if a single con- 110

tinuous lace is used and that there is no danger of the fastener breaking or wearing, no possibility of loops becoming untied or hanging down to present an untidy appearance. The operation of closing an opening with the improved fastener is much simpler and requires less effort than is necessary to pass a lace through a series of eyelets or about projecting hook-like studs, a single 10 movement serving to securely connect two sets of eyelets.

It will be seen that as the fastener conforms substantially to the curvature of the surface over which it extends it avoids entirely 15 the danger incident to exerting an undue amount of pressure at any particular point, as is frequently the case where laces are employed. In the case of a shoe fastener, for example, it exerts a uniform pressure 20 on the portions of the instep across which it passes and does not interfere in the slightest manner with the proper circulation and avoids the danger of "broken arch" and "flat foot" which are frequently due to the 25 undesirably high pressure arising from tight lacing.

When in use the transverse connecting member 3 lies between the tongue 10 of the shoe and the body in which the eyelets 5 are 30 arranged so that it does not contact directly with the foot.

Having thus described the invention, what is claimed is:

1. A fastener for the purposes described 35 comprising two bar-like members provided at one end with means for engaging eyelets and having their other ends connected by a transverse member which is concealed when the device is in use and is adapted to allow 40 the fastener to rock slightly to conform to the body over which it extends.

2. A fastener for the purposes described, comprising two metal, substantially parallel, bars connected at one end by a rigid member 45 that extends transversely of said bars throughout its length and which is bowed or

curved longitudinally, and having their free ends adapted to engage eyelets.

3. A fastener for the purposes described comprising two metal members adapted to 50 extend through a pair of eyelets and connected at one end by an integral transverse member that lies below the body supporting the eyelets when the device is in use, the other ends of said members being shaped to 55 engage eyelets at the opposite side of an opening across which the members extend.

4. A fastener for the purposes described comprising two bar-like members connected at one end by a transverse member, said bar-like members being bent so that the transverse connecting member is directed toward the free ends thereof and the latter being bent or curved to form eyelet engaging 60 hooks.

5. A fastener for the purposes described comprising two bar-like members, having a uniform slight longitudinal curvature, connected at one end by a longitudinally bowed member, that extends transversely of said 70 bar-like members throughout its length, the free ends of the bar-like members being provided with eyelet engaging means.

6. In a device of the type described, a fastener having a loop at one end, formed to 75 present a hook adapted to be reversely inserted through a pair of apertures, and at the other end hook members to engage correspondingly placed eyelets in another portion of the article to be fastened.

7. A fastener of substantially U-form 80 adapted to have its limbs passed outwardly through a pair of eyelets and having the separated ends of said limbs bent to engage eyelets at the opposite side of an opening 85 across which the fastener extends.

8. A fastener for the purpose described having at one end a transverse hook, 3, and at its opposite end two, separated, eyelet engaging members.

In testimony whereof I affix my signature.
CHARLES RYAN.
